UNITED STATES PATENT OFFICE.

EMANUEL ETTEHENIMER, OF NEW YORK, N. Y.

DESIGN FOR A FLUE STOPPER OR COLLAR.

SPECIFICATION forming part of Design No. 19,195, dated July 9, 1889.

Application filed May 13, 1889. Serial No. 310,643. Term of patent 7 years.

To all whom it may concern:

Be it known that I, EMANUEL ETTEHENIMER, of the city, county, and State of New York, have invented and produced a new and original Design for Flue-Stoppers and Stove-Pipe Collars, of which the following is a full, clear, and exact specification.

The leading feature of my design consists of a circular body having thereon series of curved lines a, drawn from a common center, of greater distance apart at their outer than at their inner ends, representing a series of clavate figures having curved stems, the lines being so shaded to impart to the figures an embossed appearance.

Reference is to be had to the accompanying photograph, forming a part of this specification, which represents a plan view of the design applied to a flue-stopper.

The center is circular and plain and the general contour of the complete design is also circular. From the central circular plain surface a series of curved lines a are drawn, the distance between them widening as they are carried outward, and as all the lines are curved in the same direction and shaded, a series of seemingly embossed clavate figures A are represented.

Upon the space near the margin and beyond the clavate figures a series of concavo-convex figures A' are drawn in imitation of scallops, the said lines being shaded to impart thereto the appearance of being embossed.

At each side of the center of the central plain surface a square figure B is drawn, representing openings, and a marginal line B' is drawn outside the scallop figure, shaded to represent an annular channel and convex border.

I claim—

A design for flue-stoppers and stove-pipe collars, substantially as herein shown and described.

EMANUEL ETTEHENIMER.
